CLAIM

The ornamental design for a combination digging and trenching tool head, substantially as shown and described.

DESCRIPTION

FIG. 1 is a perspective view of a combination digging and trenching tool showing my new design, the broken-line showing of the handle being for illustrative purposes only and forming no part of the claimed design; FIG. 2 is an enlarged top plan view thereof; FIG. 3 is an enlarged side elevational view thereof, the side opposite being a mirror image; FIG. 4 is an enlarged end elevational view thereof; FIG. 5 is an enlarged opposite end elevational view thereof; FIG. 6 is an enlarged bottom plan view thereof.
